UNITED STATES PATENT OFFICE.

GEORGE E. BLAINE, OF INDIANAPOLIS, INDIANA.

ADJUSTING-LEVER AND RATCHET CONNECTION FOR HARROWS.

No. 842,996.

Specification of Letters Patent.

Patented Feb. 5, 1907.

Application filed June 14, 1906. Serial No. 321,780.

To all whom it may concern:

Be it known that I, GEORGE E. BLAINE, a citizen of the United States, residing at Indianapolis, in the county of Marion and State 5 of Indiana, have invented certain new and useful Improvements in Adjusting-Lever and Ratchet Connections for Harrows; and I do declare the following to be a full, clear, and exact description of the invention, such as 10 will enable others skilled in the art to which it appertains to make and use the same.

This invention relates to improvements in adjusting-lever and ratchet connections for 15 harrows.

The object of the invention is to provide 20 an adjusting-lever and ratchet having means whereby the same may be yieldingly connected to the adjusting-bar of the harrow to yieldingly hold the harrow-toothed bars and 25 the teeth thereon in their adjusted position.

With the above and other objects in view 30 the invention consists of certain novel features of construction, combination, and arrangement of parts, as will be hereinafter 35 described and claimed.

In the accompanying drawings, Figure 1 is 40 a vertical sectional view through a harrow, showing an adjusting-lever and ratchet with the improved connections applied thereto; 45 and Fig. 2 is a vertical sectional view through the connections, taken at right angles to Fig. 1 on the line 2 2 of said figure.

Referring more particularly to the drawings, 1 denotes the harrow-tooth bars, on 50 which are fastened harrow-teeth 2. The bars 1 are revolvably mounted on or secured to connecting-bars 3, whereby said harrow-tooth bars may be turned or adjusted to vary 55 the angle of the harrow-teeth. Connected to 60 the harrow-tooth bars 1 are upwardly-projecting segmental arms 4, which are pivotally connected to an adjusting-bar 5.

Rigidly secured to the rear harrow-tooth 65 bar is an upwardly-projecting adjusting-lever 6, which is pivotally connected to the rear end of the adjusting-bar 5, as shown. On the pivot-bolt connecting the rear end of 70 the adjusting-bar to the lever 6 and arranged in the bifurcated lower end of said lever is a 75 segmental rack 7, with the teeth of which is 80 adapted to be engaged a locking-pawl 8, car-

ried by the adjusting-lever and operated in the usual manner.

In order that the harrow-tooth bars and harrow-teeth may be yieldingly held in their 55 adjusted positions, the forward end of the segmental rack is provided with an apertured lug or ear 9, through which is adapted to be passed a depending bolt 10, the upper end of which is secured in a bracket 12 on the 60 adjusting-bar 5. On the bolt 10 below the apertured lug 9 of the rack is arranged an upper washer 13, while on the lower end of the bolt is arranged a lower washer 14, and on said bolt between the washers 13 14 is ar- 65 ranged a coil-spring 15, against the tension of which the rack 7 bears in holding the tooth-bars on the harrow in their adjusted positions, whereby should the teeth on said bars be engaged with an obstruction the 70 parts of the harrow will yield, thereby preventing the breaking or bending of said parts, as will be understood. The action of the spring on the rack 7 serves to hold the parts 75 tight and to take up all lost motion, thereby preventing the rattling or creaking of any of the movable parts.

By placing the washers one at the top and one at the bottom of the spring on the bolt 10 the spring is compelled to press on the 80 radius of the ratchet, the top washer receiving the bearing of the ratchet in the compression of the spring, so that it yields to a radial motion, thereby preventing friction and noise.

From the foregoing description, taken in 85 connection with the accompanying drawings, the construction and operation of the invention will be readily understood without requiring a more extended explanation.

Various changes in the form, proportion, 90 and the minor details of construction may be resorted to without departing from the principle or sacrificing any of the advantages of this invention as defined by the appended claim.

Having thus described my invention, what 95 I claim as new, and desire to secure by Letters Patent, is—

In a harrow the combination of tooth-bars, 100 an adjusting-bar pivotally connected to said tooth-bars, an adjusting-lever and rack pivotally connected to said adjusting-bar, a lat-

erally-projecting bracket secured to said adjusting-bar, a bolt depending from said bracket, washers disposed on said bolt, a spring on said bolt between said washers, 5 said rack having an apertured lug or ear engaging said bolt between said bracket and the top washer.

In testimony whereof I have hereunto set my hand in presence of two subscribing witnesses.

GEORGE E. BLAINE.
